UNITED STATES PATENT OFFICE.

**HARRY R. HOLDEMAN, OF LOS ANGELES, CALIFORNIA, ASSIGNOR TO J. M. FELDMAN
CO. INC., OF LOS ANGELES, CALIFORNIA.**

DESIGN FOR A LANTERN FRAME.

Application filed February 20, 1928. Serial No. 25,493. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for Lantern Frames, of which the following is a specification, reference being had to the accompanying drawing, forming part thereof.

The figure is a side view of a lantern frame, showing my new design.

I claim—

The ornamental design for a lantern frame as shown.

HARRY R. HOLDEMAN.
